Herbert Sawasky, 31 Brewster Road W.,
West Massapequa, N.Y. 11758

Filed Aug. 14, 1970, Ser. No. 24,484

Term of patent 14 years

Int. Cl. D16—01

U.S. Cl. D61—1

FIG. 1 is a perspective view of a motion picture camera showing my new design; and

FIG. 2 is a right-side elevational view of FIG. 1, with battery pack and inverter omitted;

FIG. 3 is a rear elevational view of FIG. 2; and

FIG. 4 is a left-side elevational view of FIG. 1; and

FIG. 5 is a right-side elevational view of another embodiment of the camera of FIG. 1 wherein the battery pack and handle of FIG. 1 has been omitted and the main body portion of the housing is made slightly more rectangular on both of its sides as compared with the somewhat triangular shape of the main housing portion of the embodiment of FIG. 1;

FIG. 6 is a left-side elevational view of FIG. 5; and FIG. 7 is a rear elevational view of FIG. 5.

I claim:

The ornamental design for a portable shoulder supported motion picture camera, as shown and described.
